UNITED STATES PATENT OFFICE

149,956

DESIGN FOR A GRATER

Harry Lataner, Vinton, Va.

Application January 6, 1947, Serial No. 135,969

Term of patent 14 years

(Cl. D89—1)

To all whom it may concern:

Be it known that I, Harry Lataner, a citizen of the United States, residing in Vinton, county of Bedford, State of Virginia, have invented a new, original, and ornamental Design for a Grater, of which the following is a specification, reference being had to the accompanying drawing, forming a part thereof.

In the drawing:

Fig. 1 is a side elevation of a grater showing my new design.

Fig. 2 is a top plan view thereof.

Fig. 3 is a bottom plan view thereof with hinged support folded under.

Fig. 4 is a side elevation of the folded grater shown in Fig. 3.

I claim:

The ornamental design for a grater, substantially as shown.

HARRY LATANER.
